UNITED STATES PATENT OFFICE.

LEO HECHT, OF NEW YORK, N. Y., ASSIGNOR TO SUN RISE LAMP MFG. CO., INC., A CORPORATION OF NEW YORK.

DESIGN FOR A TRAY FOR CONSOLE SETS OR ARTICLE OF ANALOGOUS NATURE.

Application filed November 17, 1928. Serial No. 28,921. Term of patent 3½ years.

To all whom it may concern:

Be it known that I, LEO HECHT, a citizen of the United States, and a resident of the city, county, and State of New York, have invented a new, original, and ornamental Design for a Tray for Console Sets or Article of Analogous Nature, of which the following is a specification, reference being had to the accompanying drawing, forming a part hereof.

In the drawing:

for console sets or article of analogous nature; and

Figure 2 is a top plan view of the same, the parts shown in full line outline being ornamented in the same manner as the parts more fully illustrated.

I claim:

The ornamental design for a tray for console sets or article of analogous nature substantially as shown and described.

LEO HECHT.
